UNITED STATES PATENT OFFICE

148,503

DESIGN FOR A SMOKING PIPE

Margaret Van Dirsten, Bertha A. Bassett, and Harry L. Bassett, Detroit, Mich.; said Harry L. Bassett assignor to said Van Dirsten and said Bertha A. Bassett

Application July 11, 1946, Serial No. 131,472

Term of patent 7 years

(Cl. D85—8)

To all whom it may concern:

Be it known that we, Margaret Van Dirsten, Bertha A. Bassett, and Harry L. Bassett, citizens of the United States, residing at Detroit, in the county of Wayne and State of Michigan, have invented a new, original, and ornamental Design for a Smoking Pipe, of which the following is a specification, reference being had to the accompanying drawing, forming part thereof.

In the drawing:

Figure 1 is a perspective view of a smoking pipe embodying our new design.

Figure 2 is a cross-sectional view thereof taken on the line 2—2 of Figure 1.

The side of the pipe which is not shown in the drawing is identical with that which is shown.

We claim:

The ornamental design for a smoking pipe, as shown and described.

MARGARET VAN DIRSTEN.
BERTHA A. BASSETT.
HARRY L. BASSETT.
